COMPRESSION DIE

Henry Peter Dupre, New York, N. Y., assignor to
Burndy Engineering Company, Inc., a corpora-
tion of New York

Application November 15, 1943, Serial No. 510,426

1 Claim. (Cl. 140—113)

1

My invention relates to a novel form of compression die for indenting the sleeve of a connector into a conductor contained therein for securing the two together.

Hitherto such dies have been made to a size corresponding to a given diameter of sleeve. A change of sleeve size necessitated a change in the compression die parts. The principal object of my invention is to provide a compression die for accommodating a variety of sleeve diameters without changing parts. Other objects are to provide a compression die capable of accommodating a variety of sleeve diameters without damaging the sleeve by splitting it open, or thinning out the sleeve wall unduly at the bottom of the indentation.

I accomplish these and other objects and obtain my new results as will be apparent from the device described in the following specification, particularly pointed out in the claim, and illustrated in the accompanying drawing in which:

Fig. 1 is a side elevation of my proposed compression die.

Fig. 2 is a sectional view of the same indenting a maximum size sleeve.

Fig. 3 is a sectional view of the same indenting an intermediate size sleeve.

Fig. 4 is a sectional view of the same indenting a minimum size sleeve.

In the drawings, I have shown a compression die 10, having a plurality of superimposed indenting mounds 11, 12 and 13 having diminishing base areas forming annular recesses at the point of junction. That is to say, if the base of the compression die 10 has a transverse dimension "a," the largest indenting mound 11 may have a reduced dimension "b." Projecting therefrom, the secondary indenting mound 12, having a further reduced base dimension "c" is formed, and last, the smallest indenting mound 13, may have the smallest base "d." While three reductions of mound dimensions are shown, this is by way of example only, the use of two or more being contemplated, depending on circumstances.

In Fig. 2, I have shown the compression die 10, and the holding die 20, within which is contained the sleeve 21, about the conductor 22. A hydraulic tool, not shown, but possibly of the type shown in the patent to Matthysse No. 2,254,613 may be used for indenting purposes.

In this large size of connector sleeve, the three concentric mounds 11, 12 and 13 are used to establish the indentation. Where an intermediate size sleeve 23, is used, only mounds 12 and 13 enter the sleeve, as shown in Fig. 3. In Fig. 4

2

the smallest sleeve 24, is entered by mound 13 only. The holding die 20 may be used for the different sizes for I have found that a small harmless flattening of these sleeves which may occur, does not interfere with such use.

Where the compression die is not depth-controlled, and descends to the same point with each stroke, the largest size sleeve will receive the deepest impression. In the #2 AWG size conductors, an impression up to 70% of the diameter will not split or unduly thin out the metal at the lowest point due to the provision of the circumferential recesses 25 and 26, wherein the well defined lines of junction apparently establishes a firm grip on the metal in the recesses and carries the metal with it in its downward movement, maintaining a substantial thickness at the deepest point. A depth of 50% of the diameter of the #8 AWG conductor may be obtained with intermediate size conductors varying between 50 and 70%. The smallest mound may be 16% of the effective overall height of the combined mounds, and the smallest and intermediate heights may be 35% of the total height. Where the impression die may be depth controlled a uniform ratio of the depth of impression with respect to the diameter of the sleeve may be employed. The mounds may be circular, oval, or otherwise shaped at their base sections.

30 The sides of the mounds may be tapered slightly to facilitate withdrawal from the sleeve, and the tip of the die should be rounded to avoid cutting the metal.

I have thus described my invention, but I desire it understood that it is not confined to the particular forms or uses shown and described, the same being merely illustrative, and that the invention may be carried out in other ways without departing from the spirit of my invention,

40 and, therefore, I claim broadly the right to employ all equivalent instrumentalities coming within the scope of the appended claim, and by means of which, objects of my invention are attained and new results accomplished, as it is obvious that the particular embodiments herein shown and described are only some of the many that can be employed to attain these objects and accomplish these results.

I claim:

50 An indenting tool for indenting a metal tubular sleeve to a wire, said tool comprising a lower die part having a transversely extending semi-cylindrical groove for supporting a sleeve therein; a longitudinally extending indenting die having a base with encircling sides forming a tip portion

extending from the base and circumferentially rounded on all sides from the base to the center of the tip, said tip having a maximum diameter less than the minimum diameter of the base; said indenting die being provided with a shoulder having a flat face which extends transversely to the longitudinal axis of the die, said shoulder connecting said maximum diameter of the tip to the base of the indenting die; and means for controlling the distance that the indenting die is capable of moving into the sleeve supported in the semi-cylindrical groove of the lower die part, to a point substantially in excess of twice the wall thickness of the sleeve from the bottom of the semi-cylindrical groove, and less than the diameter of the sleeve. 10 15
